CLAIM

The ornamental design for a hair treatment cap, as shown and described.

DESCRIPTION

FIG. 1 is a front perspective view of a hair treatment cap, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 2; and, FIG. 10 is an enlarged detail view of area 10 in FIG. 2.

The broken lines shown in the drawings illustrate portions of the hair treatment cap that form no part of the claimed design. The short-dash-long-dash broken lines shown in FIGS. 2, 9 and 10 depict the bounds of the claimed design and form no part thereof.

The short-dash-long-dash broken lines encircling the enlarged views illustrate the bounds of the enlarged views and form no part of the claim thereof.
